Attorney

UNITED STATES PATENT OFFICE.

WILLIAM L. MCGILL, OF FOSTER, KENTUCKY.

ANIMAL-YOKE.

1,245,116.

Specification of Letters Patent. Patented Oct. 30, 1917.

Application filed May 31, 1916. Serial No. 100,831.

To all whom it may concern:

Be it known that I, WILLIAM L. MCGILL, a citizen of the United States, residing at Foster, in the county of Bracken and State of Kentucky, have invented certain useful Improvements in Animal-Yokes, of which the following is a specification, reference being had therein to the accompanying drawing.

10 This invention relates to improvements in animal yokes or pokes, one object of the invention being the provision of a humane device of this character which is readily attached in use and which is durable, inexpensive and light in construction.

In the accompanying drawings:

Figure 1 is a front elevation of the complete yoke or poke, the same being closed.

Fig. 2 is a side elevation of the same.

20 Fig. 3 is a view similar to Fig. 1, with the same open.

Referring to the drawings, two members 5 and 6, are each made from a piece of pipe, being held relatively to each other by means 25 of the curved tubular member 7 which has mounted therein the spring actuated pins 8 which project toward the shoulder of the animal and form sufficient resistance to prick the animal in attempting to jump fences or 30 go through the same.

35 A cross bar 9 is attached to both members 5 and 6 intermediate of their lower ends and the member 7 so as to brace the same and prevent their changing their relative positions.

The U-shaped neck engaging tubular member 10 is hingedly connected as at 11 to the

upper end of the member 5, while carried at the opposite end is the spring hook or catch 12 for engagement with the locking 40 socket 13, formed in the upper end of the member 6.

From the foregoing description, it is evident that the present device is readily applied upon the neck of the animal by simply 45 releasing the neck piece 10 to the position as shown in Fig. 3, and snapping the same about the neck to assume the position as shown in Fig. 1.

What I claim as new is:

In a device of the class described, in combination a U-shaped neck member, a pair of members having their inner ends curving in opposite directions, said U-shaped neck being hingedly mounted at one end upon one 55 of said members, a disengageable latch connecting the opposite end of said neck and the opposite member in closed relation, a cross bar connecting said members together, a restraining member curved longitudinally 60 in a substantially segmental form and having its opposite end portions curved back and adapted to the same curvature as the main body portion of said member and being secured against the inner sides of said members, a plurality of pins disposed in the main length of said restraining member and 65 slidable therein and being disposed at right angles to the length of said member, and springs in said restraining member forming 70 resilient backing for said pins.

In testimony whereof I affix my signature.

WILLIAM L. MCGILL.
